ALTERNATING CURRENT EXCITER LAMP
FOR SOUND REPRODUCERSRobert L. Haynes, Indianapolis, Ind., assignor to
Radio Corporation of America, a corporation of
Delaware

Application July 31, 1942, Serial No. 452,987

9 Claims. (Cl. 250—41.5)

This invention relates to an exciter lamp for providing the illumination for scanning sound track in a photoelectric sound reproducer. It relates more particularly to a type of exciter lamp adapted to be operated by alternating current or to a combination of exciter lamps adapted to be so operated and to produce a minimum of hum in the reproduced sound.

The invention involves the use of one incandescent filament of fairly large diameter adapted to provide the larger portion of the scanning light, in conjunction with a second filament of much smaller diameter and thermal capacity supplied with current in such relation to the current in the main filament that the hum produced by the smaller filament will neutralize that produced by the larger filament.

One object of the invention is to provide a light source for sound reproducers which may be operated on alternating current with a minimum of hum in the reproduced sound.

Another object of the invention is to provide an A. C. exciter lamp which will produce a minimum of hum in the photocell current.

Another object of the invention is to supply an exciter lamp with an auxiliary light source of less brilliance and higher percentage of hum for neutralizing the hum which would be produced by the main exciter lamp.

Other and incidental objects of the invention will be apparent to those skilled in the art from a reading of the following specification and an inspection of the accompanying drawings, in which:

Figure 1 is a diagrammatic illustration of one form of the invention;

Figure 2 is a section taken on the line II—II of Fig. 1;

Figure 3 is a diagrammatic elevation of a second form of the invention;

Figure 4 is a view of the filaments of the lamp shown in Fig. 3 as viewed from the right-hand side; and

Figure 5 is a schematic wiring diagram of a circuit which may be used in conjunction with the lamp shown in Figs. 3 and 4 or with the lamps shown in Figs. 1 and 2.

In the form of the invention shown in Figs. 1 and 2, the main or usual exciter lamp is shown at 10. The relatively heavy filament 11 of this lamp provides light which strikes the entrance lens 13 of a sound reproducing optical system. The lamp 10 may be of any customary type as, for example, the 10-volt, 7½-ampere type. Since the lamp 10 is of relatively low voltage it is pro-

vided with current from an ordinary A. C. source of supply through the transformer 12. A second lamp 16 is provided which has a filament 17 much smaller than that provided at 11 in the main exciter lamp. This filament, for example, might operate at 8 volts and two amperes. This lamp 16 is provided with current through an appropriate transformer 15 fed through a phase shifter 14 which serves to shift the phase of the current supplied to the filament 17 relative to that supplied to the filament 11.

The filament 17 may be imaged on the filament 11 by an appropriate lens, such as 18, and the relative illumination supplied by the filament 17 may be controlled by an appropriate iris diaphragm or analogous adjustable stop diagrammatically illustrated at 19.

The radiating surface of a given length of filament varies directly as the diameter of the wire 20 while the thermal capacity of the filament varies as the square of the diameter of the wire. For this reason, the variations in temperature of the filament 17 will be considerably greater than the variations in temperature of the filament 11. The filament 17 may therefore supply a relatively small proportion of the illumination and at the same time it will be capable of supplying light intensity fluctuations in opposite phase to those produced by the filament 11 and of sufficient amplitude to effectively neutralize the intensity fluctuations produced by the filament 11.

I am aware that it has previously been proposed to provide lamps with polyphase filaments of similar size but such arrangements have been impractical for the reason that it has been difficult to derive polyphase current from single-phase current, and phase shifting devices for accomplishing this result in conjunction with exciter lamps have been unduly expensive and difficult to adjust due particularly to the large currents and low voltages involved. In the present arrangement the disadvantages of the prior art devices have been avoided since the current which is shifted in phase is only a relatively small fraction of the total illuminating current.

Referring now to the form of the invention shown in Figs. 3 and 4: The filament 21 in the lamp 20 corresponds to the filament 11 in Fig. 1 and is relatively heavy. The image of this filament is focused by the lens 13 on the objective lens 24 of the reproducing optical system and the image of the slit 23 is focused by the objective 24 upon the film F, the light passing through the film reaching the reproducing photocell 25. The filament corresponding to the filament 17 in Fig.

1 is provided at 22 in the same envelope 20 with the filament 21. This filament 22 is, of course, somewhat out of focus, insofar as the objective 24 is concerned, but this feature is an advantage as the filament 22 may be made somewhat shorter than the filament 21 and its diffused image will completely fill the objective 24.

The appearance of the filaments 21 and 22 as viewed from the condenser lens 13 is substantially as shown in Fig. 4.

An appropriate circuit for operating the lamp of Fig. 3 is shown in Fig. 5. The usual 110 volt, 60 cycle alternating current is supplied to the transformer 30 which steps it down to an appropriate value. Current is supplied to the main filament 21 through the usual variable resistor 31 by which the current may be adjusted to the proper value. The current to the filament 22 is supplied through an appropriate phase shifting network which includes the variable resistor 35 in series with the filament 22 for adjusting the current through this filament, the reactor 32 and resistor 33 in series connected across the output of the transformer 30 and the adjustable reactor 34 connected in series with the resistor 35 and the filament 22. The value of these reactors and resistors should be so adjusted that the current through the filament 22 is substantially 90 degrees out of phase with the current through the filament 21. Since the 60 cycle current through these filaments produces 120 cycle hum frequency, this 90 degree phase shift will produce a 180 degree phase shift in the variation in brilliance of the filament 22 relative to the filament 21 and these variations in illumination will tend to cancel, producing a minimum of hum.

Inasmuch as the filament 21 is greater in diameter than the filament 22, the variations in temperature will tend to lag farther behind the current in the case of the filament 21. Inasmuch as these variations cannot be accurately predicted, the reactor 34 is preferably made adjustable so that the phase relation of the variations in illumination of the two filaments may be balanced to the best advantage.

Although the circuit shown in Fig. 5 produces a lag in the phase of the smaller filament in relation to that of the larger, it will be understood from Fig. 1 that any known type of phase shifting circuit may be used and the phase relation of the smaller filament may be advanced the proper amount in relation to that of the larger filament in order to secure minimum hum.

I claim as my invention:

1. In a photoelectric apparatus, light producing means comprising a main incandescent filament, a secondary filament of smaller diameter than the main filament and means for supplying alternating current in different phase relation to said filaments.

2. In a photoelectric apparatus, light producing

means comprising a main incandescent filament, a secondary filament of smaller diameter than the main filament and means for supplying alternating current in different phase relation to said filaments from a single phase source.

3. In a photoelectric apparatus, an exciter lamp comprising a main incandescent filament and a secondary filament of smaller diameter than the main filament, and means for supplying alternating current in different phase relation to said filaments.

4. In a photoelectric apparatus, light producing means comprising a main incandescent filament, a secondary filament of smaller diameter than the main filament and means for supplying alternating current in different phase relation to said filaments, from a single phase source and including means for shifting the phase relation of the current in the smaller filament relative to that in the main filament.

5. In a photoelectric apparatus, an exciter lamp comprising a main incandescent filament and a secondary filament of smaller diameter than the main filament and means for supplying alternating current in different phase relation to said filaments from a single phase source.

6. In a photoelectric apparatus, light producing means comprising a main incandescent filament, a secondary filament of smaller diameter than the main filament, means for supplying alternating current in different phase relation to said filaments, and means for superposing the illumination from both of said filaments.

7. In a photoelectric apparatus including a photocell, light producing means comprising a main incandescent filament, a secondary filament of smaller diameter than the main filament, means for supplying alternating current in different phase relation to said filaments, means for imaging one filament on the other filament, and means for directing light from both filaments to the photocell.

8. In a photoelectric apparatus, light producing means comprising a main incandescent filament, a secondary filament of smaller diameter than the main filament, means for supplying alternating current in different phase relation to said filaments, and means for superposing the illumination from both of said filaments.

9. In a photoelectric apparatus, including a photocell light producing means comprising a main incandescent filament, a secondary filament of smaller diameter than the main filament, means for supplying alternating current from a single phase source in different phase relation to said filaments, means for imaging one filament on the other filament, and means for directing light from both filaments to the photocell.
